LAWRENCE W. LUELLEN, OF MOUNTAIN LAKES, NEW JERSEY

CONICAL DRINKING CUP

Application filed January 31, 1927. Serial No. 164,705.

This invention relates to conical drinking cups.

The object of this invention is to provide a drinking cup of cheap manufacture made from a single piece of paper, involving the fewest possible number of cuts and/or operations in the manufacture thereof, and one in which the bottom of the cup will be tight and made without seam and also sufficiently reinforced from apex to the mouth by a plurality of layers of paper.

Another object of the invention is to provide a cup made of one piece of paper of minimum area to give the maximum capacity within the cup when formed.

Another object of the invention is to provide a cup of such configuration as will give a maximum capacity within the cup from a minimum area of paper, and at the same time so form the side walls of the cup with a plurality of thicknesses of paper entirely encircling the cup so that the contents thereof will not readily spill or run out over the brim when the cup is being used for drinking purposes.

Another object of the cup is to provide a double sealing of the bottom and reinforcing of the side wall by the encircling seam thereof.

Another object of the cup is to provide a spacing means for conical cups made of a single piece of paper, which is the same thickness throughout the circumference of the cup.

Another object of the invention is to provide a reinforced rim for the top of a conical cup by means of the entirely encircling seam.

It is a further object of this invention to provide a cup of simple and efficient construction, which may be cut from paper stock with a minimum waste of material.

It is a further object to provide a cup of the character described which can be manufactured economically by machinery.

Other objects of the invention will be in part obvious and will in part appear hereinafter.

For a fuller understanding of the nature and objects of the invention, reference

should be had to the following detailed description taken in connection with the accompanying drawings, in which:

Fig. 1 is a plan of a blank made in accordance with this invention. 55

Fig. 2 is a view showing the manner in which these blanks may be cut from the stock with substantially no waste.

Fig. 3 is a view of the completed cup.

Figs. 4, 5, and 6 are views of the cup in 60 partly assembled state, and

Fig. 7 is a top plan view.

In the particular form of the blank illustrated, the general contour of the blank is formed by a circular edge 1 having its center 65 of curvature at the apex 2 of the cup. This edge is adapted to serve as the periphery of the completed cup. The blank has two other edges which, for convenience, may be termed radial edges. One radial edge 3 extends inwardly from one termination 4 of the peripheral edge 1 to a point 5 near the apex 2. This edge 3 is curved with the same radius of curvature as the edge 1, but with its center 2^a displaced a distance equal to 70 the height of the finished cup. The edge 1 has its other or lower end 6 substantially coincident with the apex C of the blank. Also, the line joining the centers of curvature 2 and 2^a when extended will pass substantially 75 through the apex C. This line therefore passes substantially through all the apexes when the blanks are relatively arranged as in Figure 2 and for convenience is designated by CC. 80

The blank generally projects beyond the line CC to the right, as seen in Fig. 1, to form an overlapping portion 7. This is bounded by a line 8 extending upwardly 90 from the point 5 to form a re-entrant angle with the curved line 3, and by a line 9 having a radius of curvature the same as that of the line 8 and extending upwardly from the point 6 for a distance equal to the line 8, 95 say to a point 10. In practice, it is convenient to make the line 9 a curved line continuous beyond the point 10 as shown at 11 to the point where it intersects the line 8. This line 9-10-11 may be made a curve 100

with the same radius of curvature as the side 1.

By reason of the fact that the lines 1 and 3 have the same radius of curvature, and further by reason of the fact that the lines 8 and 9 have the same radius of curvature, it will be clear that the edge of the blank including the reentrant angle formed at 5 by lines 3 and 8 is complementary in form to the edge of the blank including the projecting angle 6 formed by the intersection of the lines 1 and 9. By reason of this fact, the material cut out at the point 5 from one blank serves as the projecting angle at 6 for the next adjacent blank. This will be clearly seen from Fig. 2. Thus the blanks may be cut from a continuous strip of paper with substantially no waste.

It will thus be seen from the foregoing, and referring particularly to Fig. 1, that the improved blank is generally heart shaped. Furthermore, since the blank is bounded by the four lines 1, 3, 8 and 9—10—11 it forms, when in flat condition, a quadrangular figure.

The formation of the cup from the blank is illustrated in Figs. 3, 4, 5, 6 and 7. The apex of the cup is preferably at the point 2 close to the point 5 but inside the body of the blank. The blank may be wound around a conical mandrel of such size as to cause a slight overlap of the point 6 beyond the point 4. When so wound, the projection 7 causes an increasing overlap from the periphery toward the point and permits the projection formed at the line 8 to wrap securely around the apex to reinforce the cup. When the curve of the line 9—11 has substantially the same radius as the line 1 it causes the overlap to wind about the cup as it extends toward the apex and thus strengthens the cup against distortion. The regular spiral so formed on the outside of the formed cup is also of ornamental appearance, as will be seen from Figs. 3 and 7.

The center of the mandrel is placed at 2 and the point 4 folded around it as shown in Fig. 4. The point 6 is then carried around in the opposite direction to overlap the point 4, causing the blank, at the apex to be folded upon itself tightly to close the apex, as clearly shown at 13. By thus placing the apex within the body of the cup, all danger of leakage at that point is eliminated. The point 12 is thereupon folded around the apex, covering up the apex junction 13 and insuring the tightness of the closure and at the same time reinforcing the apex of the cup. The parts may be fixed in place by paraffin, but I prefer to cement them together by a water-proof cement such as sodium silicate. The overlaps or projections 7, as they thus encircle the apexes of the cups, serve moreover, to space the cups when nested together, thus facilitating their separation from each other and avoiding bind-

ing. Moreover, this overlap strengthens the cup rim by its distributed support about the cup periphery.

With the above construction it will be obvious that the advantages of a conical paper cup are obtained which is completely watertight at the apex, which has a rigidity and strength to withstand hard usage while at the same time it is constructed from a blank which can be cut from stock with a minimum waste.

It will be obvious that under certain circumstances, where it may be desired, this series of blanks such as shown in Fig. 2 may be placed side by side with the projections of one series lying in the recesses between the other series, thus utilizing substantially all of the stock. In other words, two adjacent sides of the quadrangular blank form a counterpart of two other adjacent sides.

Thus by the above construction are accomplished the objects hereinbefore set forth.

Since certain changes may be made in carrying out the above method without departing from the scope of the invention, it is intended that all matter contained in the above description shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent is:

1. A quadrangular blank for the manufacture of a conical cup, having two opposite sides of complementary form, one said side having an outwardly convex portion for forming the edge of the conical cup.

2. A blank for the manufacture of a conical drinking cup of general heart shape, having on one side a reentrant angle and on the opposite side a projecting angle, the sides including said angles being of complementary configuration, said blank having at opposite sides outwardly convex lateral edge portions lying respectively between said first mentioned sides.

3. A blank for the manufacture of a conical cup having upon one side a projecting angle bounded by two curved edges and upon the other side a reentrant angle equal to said projecting angle.

4. A blank for the manufacture of a conical cup having its main portion bounded by a curved edge adapted to serve as the periphery of the cup and terminating at one end in a projecting angle, the other edge of said angle extending toward and beyond the apex of the cup to form an overlap.

ping edge extending beyond the apex, the remainder of said blank being defined by a reentrant angle having its apex near to but outside of the apex of the cup, the side of the blank having said reentrant angle being complementary to the side having said projecting angle.

5. A blank for a conical drinking cup, including a curved edge with its center of curvature at the apex of the cup and two radial edges extending inwardly from the ends of said curved edge toward the apex, one of said radial edges terminating adjacent to, but not at the apex, and the other of said radial edges extending beyond the apex and spaced therefrom and having its end connected to the end of the first named radial edge to form a reentrant angle whereby there is provided a projecting tab for 10 reinforcing the apex, said second mentioned radial edge forming at its juncture with said curved edge, a projecting angle forming a blank edge having a configuration complementary to the configuration of the blank edge having said reentrant angle.

25. A blank for a conical drinking cup defined in part by two intersecting circular arcs of equal radii, radially equal to the height of the cup, and centers spaced 30 apart the height of a cup, said arcs being continued from their intersection to the line joining their centers, the remainder of said blank being projected beyond said line to form an overlap defined in part by bounding lines making an angle to said line of centers, and by a line connecting the termination of said bounding lines.

35. A blank for conical drinking cups comprising a body portion defined by two circular arcs of equal radii, said arcs terminating 40 in a straight line joining their centers, and an overlap portion having its exterior sides defined by two equal lines and a connection between them.

45. 8. A blank for drinking cups comprising a body portion and an overlap portion, said overlap portion projecting beyond the apex to form a tab defined, in part, by a concave curve originating at a point adjacent the apex and extending outwardly therefrom to intersect an adjacent bounding edge of the tab.

50. 9. A blank for conical drinking cups of quadrangular form having all four edges of the same curvature, two of said edges 55 forming therebetween a reentrant angle which is complementary with a remote edge of the blank.

In testimony whereof I affix my signature.
LAWRENCE W. LUellen.
